[57] CLAIM

The ornamental design for a floating game board, as shown and described.

DESCRIPTION

FIG. 1 is a perspective view of a floating game board showing my new design;

FIG. 2 is a top plan view;

FIG. 3 is a bottom plan view;

FIG. 4 is a side elevational view;

FIG. 5 is an end elevational view; and

FIG. 6 is a cross sectional view taken on the line 6—6 of FIG. 2.

The side and end of the floating game board not shown are identical to the side and end shown.

FIG. 1

FIG. 2

FIG. 3

FIG. 3

FIG. 5

FIG. 6
